CANDLE HOLDER

Albert T. Candy, Jr., Chicago, Ill., assignor to
 Candy & Company, Chicago, Ill., a corporation
 of Illinois

Application March 20, 1941, Serial No. 384,243

4 Claims. (Cl. 67—27)

This invention relates to improvements in candle holders and particularly to candle holders of the spring-pressed type.

Candle holders of the type herein contemplated which generally comprise a rigid tubular holder body for the reception of a common candle and a spring to urge the candle upwardly as it is consumed, the exposed wick portion of the candle projecting outwardly through an opening or apertured cap at the top of the holder. Such candle holders are generally used for maintaining the candle flame at a fixed elevation, for the prevention of candle dripping or distortion in warm atmospheres or rooms, for ornamental use, or for votive, sanctuary or other sacramental light use.

Heretofore such candle holders have been made with the tubular body portion formed wholly or substantially of metal or equivalent materials, making the cost of the unit relatively high with respect to the cost of the candle per se, so that economical use required preservation of the holder and replacing only the candle when consumed. Such reuse of the holders, however, is not always satisfactory, since internal drippings may accumulate, holders become worn and lose their decorative appearance in use, and even after having been used but once there is considerable evidence thereof at the cap portion of the holder. Additionally such refilling of candles requires manipulation by engagement or disengagement of parts which is not always feasible or desirable, and at times even renders subsequent re-use hazardous due to wearing of engagement parts or faulty reassembly.

It is therefore an object of the present invention to provide a candle holder of the spring-pressed type which is economical to manufacture and use and which may be discarded after having been once used, and due to such economy the candle holders may be used and made in greater number and variety, with greater safety and ease, and with better ornamental and aesthetic effect.

An additional object relates to the component materials of my candle holder and their association with each other, and particularly the construction of my uppermost retaining cap and the engagement thereof to the tubular holder portion.

Other objects relate to various details of construction and arrangement of parts, and the economies thereof which will be apparent from a consideration of the following specification and drawing, wherein:

Fig. 1 is an elevation of my improved candle holder, largely in section.

Fig. 2 is a fragmentary elevation of my candle holder with parts in section, illustrative of the top closure cap thereof preparatory to bringing it into locking engagement with the tubular hold-

er body, in accordance with one form of my invention.

Fig. 3 is a view similar to Fig. 2 illustrating a modified form of construction and another method of bringing about engagement of the top closure cap with the tubular body.

Fig. 4 is a plan view of Fig. 1.

Fig. 5 is a plan view of Fig. 2.

Fig. 6 is a fragmentary elevation in section of the base portion of my candle holder and an engaged adapter, illustrating one form of construction and relative engagement of the said parts.

Fig. 7 is a view similar to Fig. 6 illustrating a modified form of construction.

Referring to the drawing, and particularly to Fig. 1, there is illustrated my improved spring pressed candle holder comprising the tubular body member 10 having a top closure cap 11 engaged thereto, a candle 12 being contained within the tubular holder and being pressed upwardly against the cap 11 by means of the coil spring 13 and candle follower 14, the candle wick 15 projecting through the opening 16, of the annular cap 11. The candle holder may be suitably engaged in a candle stick diagrammatically illustrated at 17 by means of a generally conical adapter 18.

As previously indicated, the tubular portions of candle holders of the class herein contemplated have generally been formed wholly, or substantially wholly, of metal or the like costly and rigid materials. As distinguished therefrom I form the tubular portion 10 of my candle holder preferably of a fibrous material, such as a molded fibrous tube, or even more economically of laminated paper or cardboard wound in the form of a tube. When formed of such relatively economical fibrous material, the said tubular body may be formed of relatively low grade fibrous material such as is commonly used in the formation of tubes, boxes and the like, and I may thereafter suitably provide a decorative, ornamental, or imprinted outer wrapper to the tube 10. In this manner a highly ornamental or economical tube may be formed, and by providing standard sizes of tubes I may cause them to be ornamented and decorated in a multitude of styles and designs suitable for various purposes and occasions, and it will be appreciated in a much simpler and more economical manner than can be had with the use of metallic tubes of relatively greater expense.

As illustrated in Figs. 2 and 3, when employing tubes of relatively inexpensive fibrous material as contemplated by my invention, I may provide a series of longitudinally spaced apertures 19, particularly adjacent to the upper portion of the tubular member 10 so as to permit the user thereof to readily observe the state of consumption of the candle 12, and in this man-

ner the user may particularly determine when the candle has become substantially consumed. If desired, these sight openings 19 may be closed by transparent film material such as cellulose acetate, regenerated cellulose or the like.

The top closure cap 11 as more particularly illustrated in the detailed view of Fig. 2, comprises an annular member, the opening 16 of which is sufficiently large to permit the wick 15 to fully pass therethrough and to permit free formation of a slight pool of molten material at the base of the exposed wick portion. The central portion of the cap 11 is preferably dome shaped for better positioning and contact with the candle as it is being consumed and simulation of the top thereof, and additionally comprises the downwardly depending tubular portion 20 which telescopes within the tube 10, and the annular flange 21 which projects outwardly of the periphery of the tube 10. In the form of my invention as illustrated in Fig. 2, the tube 10 and cap 11 are assembled as illustrated, that is, the cap 11 is telescoped by means of its cylindrical portion 20 into the tube 10, and thereafter the flange 21 is turned downwardly against the outer face of the tube 10 and impressed into the material thereof to provide a bead-like locking engagement therewith as best illustrated in Fig. 1, so as to hold the edge portion of the tube 10 clamped between the cylindrical portion 20 and the bead 23.

If desired I may provide the tube 10 with an annular seat formed in its outer face adjacent the top edge thereof as illustrated at 22 in Fig. 3, and pre-form the bead 23 as shown in said figure by causing the flange 21 to be downwardly return bent, and engagement caused between the cap and the tube by inserting the tubular portion 20 thereof within the tube 10 and thereafter pressing it downwardly until the bead 23 becomes locked within the annular seat 22.

Thus I may engage the metallic cap portion 11 to the fibrous tube member 10 in the manner and by the means illustrated and described with respect to Figs. 2 and 3, so as to cause a firm locking engagement between the two portions as illustrated in Fig. 1. It will be apparent that although my tube 10 is of fibrous material such as paper, by forming my cap 11 of metal and providing it with the downwardly depending portion 20 telescoped within the tube 10 adjacent its upper and most heated portion, my tubular portion 20 affords sufficient insulation thereto for protection and preservation of the fibrous material of the tube, and sufficiently so in view of the fact that it is contemplated that the tube 10 and its attached cap 11 will be discarded after the burning of a single candle therein.

Since candles of this nature have relatively rigid tubular portions even when constructed of fibrous material in accordance with my invention, it is desirable that conical or tapered adapters be secured to the base of the holder to permit the device to be readily mounted in the candle stick, such as the one diagrammatically illustrated at 17. These adapters may be formed of metal, rubber, molded plastics, or the like materials and they may even be formed of fibrous materials. As illustrated in Fig. 6, I may provide the adapter 18 as a unitary portion of the spring pressed candle holder, the tube 10 being open at its base and the coiled spring coming to rest within the adapter, the adapter 18 and the tube 10 being engaged to each other by suit-

able means such as for example, the annular depression 24, to cause firm frictional engagement with the tube 10 and may be supplemented by a clamping ring or spring. If it should be desirable to preserve the coiled spring 13 which is the most expensive portion of the assembly, in the form of construction illustrated in Fig. 6, the adapter 18 may be readily separated from the tube 10 and the spring preserved for re-use with 10 a new tube, since the spring 13 is at all times concealed and re-use thereof is without objection. However, I may provide a construction shown in Fig. 7 wherein the tube 10 is provided with a base closure member 25 retained by means 15 of the rolled edge 26 of the tube 10, the adapter 18 being engaged to the tube 10 in a manner similar to that described in Fig. 6.

It will thus be seen that I have provided a relatively inexpensive candle holder of the spring pressed type, the whole of which may be discarded after being used but once, is relatively economical to make and safe in use, and which lends itself more readily to decoration and ornamentation, and permits users of candles of this type to use them with greater efficiency and greater variety, and opens up a field of use to those to whom such use has heretofore been restricted for economic or aesthetic reasons.

I claim as my invention:

30 1. A candle holder of the class described comprising a unitary tube portion formed throughout its entire length of fibrous material and a unitary annular metallic top closure and candle top abutment therefor; the said cap being in 35 fixed embracing engagement with the interior and exterior faces of the upper edge portion of the fibrous tube.

2. A candle holder of the class described comprising a unitary tube the full length thereof being formed of fibrous material, and a unitary annular metallic candle tube abutment cap therefor in fixed engagement therewith, the said cap comprising a cylindrical projection telescoped within the upper edge portion of said tube and 45 an annular return bent flange portion pressed against the outer surface of said tube adjacent the upper edge thereof to cause said tube to be clamped between said cylindrical projection and said flange portion.

3. A candle holder of the class described comprising a unitary tube the full length thereof being formed of fibrous material, and a unitary metallic tube abutment cap therefor in fixed engagement therewith, the said tube comprising an annular seat formed on the outer surface thereof adjacent its upper edge and said cap comprising a cylindrical projection telescoped within said tube and lying firmly against the inner face adjacent the upper edge portion thereof and an annular return bent flange portion extending into said annular tube seat to thereby maintain the cap in firm and fixed engagement with the tube.

4. A candle holder of the class described comprising a spring-pressed candle retaining tube formed throughout its entire length of fibrous material, a unitary annular metallic candle top abutment cap engaged over the upper edge and clamped by means of integrally extending portions to the interior and exterior faces of the tube and in fixed engagement therewith, and a tapered adapter in engagement with said fibrous tube adjacent the base thereof.

ALBERT T. CANDY, JR.
